Arthur B. Jenkins
ATTORNEY

UNITED STATES PATENT OFFICE.

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

HANDLE LOCK.

Application filed March 4, 1922. Serial No. 541,134.

My invention, while not limited in its application, relates more especially to that class of locks employed for locking spindles of latches, knobs, &c., and an object of my invention, among others, is to provide a lock of this class that shall be extremely strong and particularly efficient for the purpose for which it is intended.

One form of lock embodying my invention, and in the construction and use of which the objects herein set out, as well as others, may be attained, is illustrated in the accompanying drawings, in which—

Figure 1 is a front view of my improved lock shown as applied to a latch spindle having a handle secured thereto.

Figure 2 is a side view of the same.

Figure 3 is a rear view with the handle broken off.

Figure 4 is a view in section on a plane denoted by the dotted line 4—4 of Figure 5.

Figure 5 is a view in central longitudinal section through my improved lock structure and with parts broken away to show construction.

Figure 6 is a view similar to Figure 5 and of a portion thereof but showing the lock case in its unlocked position.

My invention, as hereinbefore stated, is not limited in its application to any particular structure, but as it is especially adapted for the purpose of securing the spindle of a latch as constructed for automobile doors against rotation, I have selected a structure of this class for the purpose of illustration of my invention herein, the numeral 7 indicating a lock case that may be arranged in any suitable manner for insertion in a mortise, as in a door, and that to this end has a flange terminating the edge of the face 8 of the case with ears 9 to receive screws or other fastenings for securing the case in place. A latch spindle 10 extends through the case 7 and is provided with a handle 11, of any suitable form, rigidly secured thereto, a tip 12 of the spindle being of proper form, as square, for engagement or connection with the latch of a latch lock for a door, such parts and connections not being shown herein, as being of ordinary construction they will be readily understood by those skilled in the art.

The spindle 10 has a recess 13 to receive a spindle locking bolt 14 extending through an opening 15 in a wall dividing the hole

16 for the spindle from a bolt chamber 17 opening out from a barrel chamber 18 in the lower part of the lock case.

A key barrel 19 containing a key cylinder 20 is located in the chamber 18, this barrel and cylinder, so far as the locking elements are concerned, being of any ordinary construction, and for which reason a detailed description and illustration are omitted herein, the key center 21 only being shown.

A crank pin 22 projects from the inner end of the cylinder 20 into a notch in the side of the bolt 14, this notch 23 being of considerable length to permit movement of the locking bolt independently of the pin 22.

This bolt may be forced normally toward the spindle 10, as by means of a spring, said bolt passing through an opening 24 from the interior of the key barrel 19. A cap 25 closes the rear end of the barrel chamber 18, and a

spring or springs 27 located in an opening or openings in the key barrel and pressing against said cap operates to force the key barrel to its outward position, and as shown in Figure 6 of the drawing. A key slot closure 26 is rotatably attached to the barrel 19 as a means for closing the key slot when not in use.

In the operation of the device, supposing the parts to be in locked position, as shown in Figure 5, insertion of a key in the key slot will position the tumblers so that the cylinder 20 may be rotated, as by turning the key, and this will operate the crank pin 22 to withdraw the locking bolt 14 from engagement with the recess 13.

Immediately upon such withdrawal of the locking bolt the spring or springs 27 will force the key barrel outwardly to the position shown in Figure 6, in which position the locking bolt 14 will be carried to the forward part of the chamber 17 and out of alignment with the opening 15, said bolt in this position resting with its end against the bottom wall of the chamber.

The parts being thus unlocked the spindle 10 may be freely turned to operate the latch to permit the door to which the parts are secured to be opened. To lock the parts it is necessary only to push the barrel 19 inwardly, as by pressure of the thumb, the bolt 14 springing into locked position through the opening 15 and into the recess 13 when the bolt reaches a position to register with said opening and recess, and provided the latch spin-

dle is in proper position. If said spindle is not in proper position at this time, the locking bolt will rest against the side of said spindle, but just as soon as the latter is turned to cause engagement of the latch with its keeper, the recess 13 will be located in proper position to receive the locking bolt and thus lock the parts.

If it be desired that the bolt 14 shall not automatically operate to lock the parts, the spring for actuating said bolt and as shown in Figure 5 may be omitted, in which case the locking bolt will be moved to locked position only by operation of the key. My invention contemplates any structure in which the locking bolt 14 is temporarily held against movement in its unlocked position and by means of a member that may be mounted to move in various ways to release said bolt, and while in accordance with the provisions of the patent statutes I have described the principles of operation of my invention, together with the device which I now consider to represent the best embodiment thereof, I desire to have it understood that the device shown is only illustrative and that the invention may be carried out by other means.

I claim—

1. A spindle, a movably mounted operating member, a locking bolt carried by said operating member to engage said spindle to lock it against movement, and means to receive the same locking bolt to lock the same operating member against movement.

2. A spindle, a movably mounted operating member, a locking bolt carried by said operating member, means to receive the locking bolt to lock said operating member against movement, means on the spindle to receive said locking bolt, and means to receive said locking bolt to retain it in unlocked position.

3. A lock case having a hole for a spindle and a lateral opening into said hole, a spindle rotatably mounted in said hole and having a recess adapted to register with said opening, an operating member movably mounted in said case, a locking bolt carried on said operating member in position to pass through said opening into the recess in said spindle, and means on the operating member for actuating said bolt.

4. A lock case having a hole for a spindle, a locking bolt chamber, and an opening from said chamber into said hole, a spindle rotatably mounted in said hole and having a locking bolt recess, an operating member movably mounted in the case, a locking bolt carried by said operating member and movable thereby in said chamber to pass through said opening and engage a recess in said spindle, or to engage the wall of said cham-

ber and thereby be prevented from passing through said opening, and means for actuating said locking bolt.

5. A lock case having a hole for a spindle, a locking bolt chamber, an opening from said chamber into said hole, and a key barrel chamber, a spindle rotatably mounted in said hole and having a locking recess, a key barrel movable in said key barrel chamber, a key operated member carried by said barrel, and a locking bolt carried by said barrel and operatively engaged with said key operated member, said bolt being movable to pass through said opening into the recess in said spindle, or to be carried into position to strike the bottom wall of said chamber.

6. A spindle, an operating member movably mounted, means for forcing said operating member in one direction, a locking bolt carried by said operating member to engage a recess in said spindle to lock it against rotation, and means to receive said locking bolt to lock said operating member.

7. A spindle, an operating member movably mounted, a locking bolt carried by said operating member to lock both the latter and said spindle against movement, and means for retaining the locking bolt in its unlocking position.

8. A spindle, an operating member movably mounted, a locking bolt carried by said operating member to engage said spindle to lock it against rotation, means carried by said operating member to actuate the locking bolt, and means to permit movement of the locking bolt independently of the operating member.

9. A rotatable spindle a bolt to engage said spindle to lock it against rotation, lock mechanism directly connected to said bolt to positively operate it, and means shiftably mounted to also control operations of said bolt.

10. A lock having a longitudinally movably mounted operating member, a bolt carried by said member, and means including said bolt to limit the longitudinal movement of said operating member.

11. A lock having a movably mounted operating member, a bolt carried by said member, and means including said bolt to prevent rotating movement of said operating member.

12. A rotatable spindle, a bolt urged to engage said spindle to lock it against movement, lock mechanism including a longitudinally movably mounted member that carries said bolt, locking means carried by said member to operate said bolt, and means to prevent operation of said bolt.

ELMER B. STONE.
